UNITED STATES PATENT OFFICE.

JUSTUS J. ROSS, OF FAIRMONT, WEST VIRGINIA.

BRAKE MECHANISM.

1,042,038.

Specification of Letters Patent. Patented Oct. 22, 1912.

Application filed March 3, 1909. Serial No. 481,127.

To all whom it may concern:

Be it known that I, JUSTUS J. Ross, a citizen of the United States of America, and resident of Fairmont, county of Marion, and 5 State of West Virginia, have invented certain new and useful Improvements in Brake Mechanism, of which the following is a specification.

This invention relates to improvements in 10 car-controlling brakes, and more particularly to a brake adapted for use on mine-tipples whereby the movement of the cars being loaded at the tipple may be controlled; and it consists in the particular construction, arrangement and combination of 15 parts which will hereinafter be fully described.

The primary object of the invention is to 20 provide a simple, positive and conveniently-operated drum brake for use on loading tipples and the like whereby the movement of railway cars from one position to another with respect to the loading chute of the tipple may be readily controlled from the 25 top of the tipple and, consequently, without resorting to the use of the brakes on the cars, resulting in the need of a man for operating such car brakes being dispensed with.

As is well known, the railway tracks at a 30 loading tipple are usually arranged on a slight incline for facilitating the forward movement of the cars as needed for loading and after loading. By means of the present invention, cars are readily released and 35 allowed to move slowly forward down the incline, and are readily stopped at any desired point.

A further object of the invention is to 40 provide a strong and durable brake of the character mentioned, the construction being such as to readily withstand the great strains and heavy shocks to which it is liable to be subjected.

In describing the invention in detail, reference is herein had to the accompanying drawings, forming a part of this specification, in which—

Figure 1 is a front elevation of the invention mounted in operative position; Fig. 2 50 is a side elevation of the same; Fig. 3 is a top plan view of the same; and Figs. 4 and 5 are sections taken respectively on the lines 4—4 and 5—5, Fig. 3.

Referring to said drawings, in which like 55 reference characters designate like parts throughout the several views—1 indicates

the base-plate of a frame which is adapted to be mounted upon a beam 2, or in other appropriate position at the top of a loading tipple, said frame comprising said base-plate 60 1 and a pair of outwardly-directed parallel supporting arms 3 and 4 which are preferably integral with the plate 1 and which are terminated by shaft-bearing portions 5 and 6, in which latter is journaled a shaft 7. 65

A drum 8 is keyed upon the shaft 7 between the arms 3 and 4 by means of a key 9 fitting in registering mortises provided in said shaft and in the drum, as is clearly shown in Figs. 4 and 5, and upon this drum 70 is wound a cable 10 one end of which is appropriately attached to said drum, as shown in Fig. 4. Said cable is passed downward from the drum to and about a sheave 11, and thence forward for connecting to a car. 75

A brake-wheel 12 is fixed upon the shaft 7 adjacent to the bearing portion 5, a key 13 being fitted into registering mortises provided in said shaft and said wheel, as shown in Figs. 2 and 5. Partially encircling 80 the wheel 12 is a flexible metal brake-band 14, on the inner surface of which is carried a sectional brake-shoe 15 of wood or other suitable material adapted for frictionally engaging said wheel. One end of the brake- 85 band 14 is connected by means of a strap 16 to the outer end of a forwardly-directed support 17 which is carried by, or which is formed integral with, the frame, and the opposite end of said band is connected by 90 means of a link or bolt 18 to the point or end of a lever 19 which is pivotally mounted intermediate its ends upon said support 17. The bolt 18 is designed as an adjusting bolt whereby slack in the brake may be readily 95 taken up, and the connection between said bolt and the lever 19 is a pivotal one, as shown at 20. Carried upon the opposite or free end of the lever 19 is a weight 21, preferably adjustable, whereby force is applied 100 to the brake-band for normally maintaining the brake applied to the wheel 12, resulting in the drum 8 being maintained in a stationary position.

The support 17 is formed integral with 105 and receives support from the arm 3, as is clearly shown in Fig. 2. Said support is of hollow box-like formation, providing two parallel vertical members 17^a, an upper cross member 17^b and a downwardly and 110 inwardly inclined member 17^c. The inner member 17^a is in vertical alinement with the

arm 3, while the opposite member 17^a overhangs the brake-wheel in appropriate position for having the lever 19 mounted thereagainst in proper relation to the brake-band 14. The two members 17^a serve as supports or separated bearings in which are held the strap-attaching bolt 22 and the pivot-bolt 23.

In practice, the weight 21 occupies a position on the lever which will normally maintain the drum stationary. When the free end of the cable has been attached to a car and it is desired to allow the car to move forward down the inclined track, the weight is either moved forward along the lever, or the free end of the latter is raised, relieving the normal pressure of the brake-shoe upon the brake-wheel. This action allows the shaft 7 and the drum 8 to turn, paying out the cable 10. It is obvious that by manipulation of the lever the speed of the car in moving forward may be readily controlled and the car may be stopped at any desired point.

The device may be operated by the same person who controls the dumping of the mine cars at the top of the tipple.

Having thus described my invention, what I claim as new, and desire to secure by Letters Patent, is—

In a drum-brake for use on loading tip-
ples, a base-plate adapted for mounting in
vertical position; a pair of parallel out-
standing arms carried by said base-plate; a
shaft journaled in said arms; a drum fixed 35
on said shaft; a brake-wheel fixed on said
shaft; a hollow box-like support connected
to one of said arms, said support comprising
a pair of parallel vertical members, an
upper cross-member, and a downwardly and 40
inwardly inclined member, the inner of the
vertical members being in vertical alignment
with said one arm and the outer of
said members being in overhanging relation
to said brake-wheel; a brake-band en- 45
circling said brake-wheel; a strap connect-
ing one end of said brake-band to the outer
end of said support; a lever pivoted inter-
mediate its ends against the brake-wheel-
overhanging member and having an end 50
pivotally connected to the opposite end of
said strap, and means for adjusting said
brake-band.

In testimony whereof I affix my signature in presence of two subscribing wit- 55
nesses.

JUSTUS J. ROSS.
